UNITED STATES PATENT OFFICE

2,530,716

CARBURETOR

Jacques Marie Jean Frédéric Meynier, Lausanne, Switzerland; Rosine Jeanne Grange Meynier sole heir of said Jacques Marie Jean Frédéric Meynier, deceased

Application April 6, 1946, Serial No. 668,056
In France August 7, 1939

Section 1, Public Law 690, August 8, 1946
Patent expires August 7, 1959

1 Claim. (Cl. 261—99)

1

My invention has for its object a carburetter chiefly for internal combustion engines characterized by the following features which may be applied simultaneously or separately.

In the first place the carburation of the air is effected by constraining the air to lick one surface of a porous partition which may be of porous china or the like earthenware and the other surface of which is in contact with the liquid fuel.

Furthermore the porous wall may assume the shape of two coaxial cylindrical elements between which a space is provided for containing the fuel.

According to a still further feature of my invention, a sliding sleeve may move inside the cylinder under the action of the depression in the engine so as to modify the operative surface of the china which is actually licked.

Lastly, carburation for idling of the engine may be obtained through a licking or sweeping action of the air over the outer wall of the outer cylinder, while carburation for power operation is obtained through a licking or a sweeping of the air over the internal surface of the inner cylinder. Or again the reverse arrangement may be provided.

I will now describe by way of example, and by no means in a limited sense, a form of execution of a carburetter according to my invention. Said form of execution is illustrated in accompanying drawings wherein

Fig. 1 is an axial cross-section,

Fig. 2 is a cross-section through line 2—2 of Fig. 1.

The carburetter includes a cylindrical casing 1 provided at its lower end with a certain number of perforations 2; the space inside said cylindrical casing 1 is closed at its lower end by a transverse partition 3; said partition 3 is provided with a central opening 4 forming a conical seat.

The lower compartment 5 bounded by or formed inside the bottom member 6 communicates with the outer atmosphere through ports 7 adapted to produce a circulation of air through the casing which is much more considerable than that afforded by the perforations 2.

The partition 3 carries in a fluid tight manner a body 8 of porous material, for example of the china material used generally for filtration purposes, and including an inner annular element 9 and an outer annular element 10, said elements being connected at their upper end through the transversal member 11. The porous body 8 is advantageously made of one part. It provides between the elements 9 and 10 an annular interval

2

or chamber 12 communicating with a reservoir or a supply of liquid fuel.

Inside the annular interval or chamber 12 is arranged a plunger tube 12a which may be of capillary size and which stretches up to a point very near the connecting member 11 and opens into the atmosphere above the liquid inside the chamber 12.

Inside the central chimney 13 of the body 8 is arranged a movable closing member 14 which is substantially sleeve-shaped and which terminates at its lower end in a conical part 15 cooperating with the seat 4. The movable closing member 14 moves over and along a guiding member 14a rigid with a spindle 16 secured to the transverse partitions 17 and 6. A spring 20 is inserted between the guiding member 14a and the conical part 15.

The weight of the movable closing part 14 is chosen in relationship with the size of the chimney 13.

The porous body 8 carries an upper transverse partition 17 separated towards its periphery from the casing 1 by an annular gap 18; the central part of said partition 17 is provided with perforations 19.

The concave portion 21 forming the upper part of the casing 1 opens into an admission pipe 22 the entrance into which is controlled by an admission throttle valve 23. A pipe 24 provides for the admission of gasoline into the annular chamber 12.

The operation of my improved carburetter is as follows:

For idling, the conical part 14 rests on the conical seat 4 as illustrated in Fig. 1. The air sucked in by the motor enters then into the carburetter through the perforations 2 and flows through the interval comprised between the outer annular element 10 and the casing 1. The air licks the outer wall of said element whereby it becomes loaded with gasoline or the like liquid fuel; it then reaches the admission pipe 22 through the annular gap 18.

The pipe 12a serves to blow off the air pushed ahead by the in-flowing gasoline.

The weight of the movable member 14, its diameter, its length, the strength of the antagonistic spring 20, the weight of the whole system, the diameter of the inner element 9 form means allowing a very simple and very accurate adjustment.

What I claim is:

A carburetter for liquid fuel in internal combustion engines comprising an outer perforated

cylindrical casing, an element of porous material mounted inside the casing with a narrow annular gap between it and said casing, said element being constituted by two substantially coaxial cylinders defining between one another an annular chamber for a liquid fuel, means for admitting said liquid into the lower end of said chamber, means for venting the air from the upper end of said chamber, a support for the porous element secured to the casing provided with an inner chamber communicating with the atmosphere and with the chamber defined by the inner cylinder, a valve adapted to close the communication between the chamber in the support and last mentioned chamber, a spring urging said valve into its operative closing position, against the suction of the engine and means whereby the engine is adapted to suck air through the perforations of the casing and through the support and to cause the same to sweep over the wall of the outer cylinder and over the inner wall of the

inner cylinder and to be laden thereby with vaporized fuel.

MEYNIER, JACQUES MARIE JEAN
FRÉDÉRIC.
